JOHN WARREN VEDDER, OF WORCESTER, MASSACHUSETTS, ASSIGNOR TO RICE, BARTON & FALES, INCORPORATED, OF WORCESTER, MASSACHUSETTS, A CORPORATION OF MASSACHUSETTS

PAPER DRIER

Application filed December 29, 1930. Serial No. 505,268.

The principal object of this invention is to provide for allowing paper in a paper drier used in connection with paper making machinery to shrink naturally, and where-
5 by the undue reduction in width of the paper now usual and the corresponding reduction in the strength of the web will be avoided.

Other objects and advantages of the invention will appear hereinafter.

10 Reference is to be had to the accompanying drawing, in which

Fig. 1 is a side view of a paper drier partially diagrammatic, showing the application of this invention thereto; and

15 Fig. 2 is an end view showing one of the drying drums.

The ordinary paper drier on the market consists of a series of drying drums arranged in an upper and lower tier and geared together. The web of paper passes around each drum and must necessarily move in accordance with the surface speed of the drum. Two felts are used, one to press the paper against one tier of drums, and the other against the other tier. These felts are driven at the surface speed of the drums by the drums, and tend to force the paper still more accurately to move at the same speed as the surface speed of the drums. The purpose, of course, of the drier is to dry the paper and the effect is not only to dry but to shrink it. Inasmuch as these driers are constructed so that the paper cannot shrink lengthwise, the entire shrinkage occurs cross-
25 wise. The result is that when the paper is dried it has shrunk unduly in width and this shrinkage is not uniform. Furthermore as the natural tendency of the paper is to shrink while on the surface of each of the drums and between the drums and that tendency is practically restrained lengthwise by the conditions above mentioned, the strength of the web is apt to be materially reduced.

With this invention these difficulties are avoided by eliminating the gears and employing pulleys and a belt to drive the drums. The pulleys are graduated in size to provide for the shrinkage. Furthermore, the belt will be able to slip when subjected to undue strain caused by the shrinkage of the paper

and allow the paper to go through without so much tension being applied to it by each drum. The result of this is that the paper is allowed to shrink longitudinally in a natural manner, and therefore, does not shrink unduly laterally and is not weakened by shrinkage.

55 The web of paper 10 passes throughout a drying machine comprising a series of internally steam heated drying drums 11 arranged in two tiers, one below and one above and staggered, so that the machine occupies practically the same space as the old machines containing the same number of drums.

60 On the shaft or journal 12 of each drum is located a pulley 13. A belt 14 is threaded over and under these pulleys 13 as shown, and driven from any desired source of power, preferably through the first upper and lower drums. The result, of course, is to drive the drums in the proper direction to feed the 70 web 10 through from one end to the other. A belt tightener 16 can be employed if desired.

65 In case the number of drums desired to use in a drier is too large to make this method practical, the drier can be split up into two or more sections with a belt for each one. The usual felts 17 and 18 are employed for holding the web against the various drums, these felts extending practically half way around each drum, one felt being used for the lower tier of drums and one for the upper tier. The felts are capable of slipping a little so as not to prevent the natural 75 shrinkage of the paper.

80 In operation, of course, the power is received by the drums through the belt 14 which rotates them. The pulleys 13 are made so that the one at the end at which the paper enters is the smallest one, and the one at the end at which the paper leaves the drier is the largest one. The others vary by very slight gradations from one end to the other, gradually increasing in size from 85 the entrance to the discharge end, but the total increase is very small. In this way the drums near the discharge end rotate a little slower progressively all the way from one end of the drier to the other. This is to take 90 up the decrease in length of the web due to 95

shrinkage. The change in diameter of the pulleys may be produced by turning them to different diameters, but usually they are all turned the same size and lagging is applied to effect the difference.

As the web enters the machine it goes around the first drum and is held thereon by the felt and then passes around the second drum. Naturally being dried a little more, 10 the web on the second drum shrinks slightly and this drum, although exactly the same size as the first drum, is rotated a little slower so that the shrink in the web of paper will be taken care of. The speed of the web 15 around this drum will be enough less to avoid any extreme tension on the web between the drums. The same condition exists all the way through the machine and therefore the web on each drum, although tightly 20 held to the surface thereof and rotating at the speed of the drum, will not be pulled to pieces by the last drum over which it goes and thereby weakened. Furthermore, it will lie naturally on the surface of each drum, 25 so that the shrinkage can take place in the natural manner.

Although I have illustrated and described only a single form of the invention, I am aware of the fact that modifications can be 30 made therein by any person skilled in the art without departing from the scope of the invention as expressed in the claims. Therefore I do not wish to be limited to the exact form shown, but what I do claim is:—

35 1. In a drier for web material, the combination of a series of heated drier drums of the same diameter over which the web is led from one drum to another, a pulley on the shaft of each drum, said pulleys being of 40 different sizes, those at the wet end being progressively smaller than those at the discharge end, a belt passing around said pulleys, one after the other, means for driving one or more of the drums from a source of power 45 so that the rest of the drums will be driven at progressively lower speeds by the belt as the web progresses through the series but these speeds will not be positive, and a felt

arranged to pass over the web throughout the series of driers so that the driving of the driers by the belt and the driving of the driers by the felt, both of which are non-positive, will control each other and allow the 70 drums to slip on the felt sufficiently to allow for the lengthwise paper shrinkage.

2. In a paper drier, the combination of a series of internal heated paper drying drums, each drum having a shaft, a pulley on each 75 shaft, the pulleys at the receiving end of the drier being of progressively smaller diameter than those at the discharge end, a belt extending over all the pulleys on the drum in a regular series, means for driving one of the 80 series of drums from an external source of power, and a felt passing over the web of paper on the drums, whereby the natural shrinkage of the web longitudinally will be accommodated by the slower speed of the 85 drums from one end of the series to the other and the shrinkage will be prevented from being transmitted to the drums positively by the fact that the felts will slip on the drums to allow the belts to drive them in spite of 90 the shrinkage.

3. In a paper drier, the combination of a series of internally heated paper drying drums arranged in two tiers, one over the other and staggered, a shaft for each drum, a 95 pulley on each shaft, the pulleys at the receiving end of the drier being of progressively smaller diameter than those at the discharge end, a belt extending over the pulleys of the upper drums and under the pulleys of 100 the lower drums to drive the drums frictionally, means for driving one of the drums from an external source of power, and endless felts extending over the drums for holding the paper against the respective drums, said 105 felts being driven by contact with the paper around the drums, whereby the friction of the belts on their pulleys plus the pull of the paper will allow the drums to slip on the felts to accommodate the longitudinal shrinkage 110 of the paper web.
